Fig.1.

Fig.2.

Fig.3.

Fig.4.

FIG. 1 is a top, front, perspective view and FIG. 2 is a bottom, rear perspective view of a building block showing my new design; and

FIG. 3 is a top, front, perspective view and FIG. 4 is a bottom, rear perspective view of a modification of the building block showing my new design.

The dominant feature of applicant's building block design resides in a plurality of evenly spaced, vertically and deeply striated panels of uniform width on at least the outer face of the building block, and additionally on end faces of corner blocks.

I claim:

The ornamental design for a building block, substantially as shown and described.
